METHOD OF MAKING COMFORTERS

Julius Davis, New York, N. Y.

Application December 19, 1936, Serial No. 116,682

5 Claims.

(Cl. 5—334)

This invention relates to methods of making comforters.

Comforters having a filling consisting entirely of down are expensive by reason of the cost of the down and the laborious method of manufacture due to the difficulty in producing an even filling especially in course of stitching. The stitching serves to avoid shifting of the down, and must be very tight to prevent down from working through the minute openings formed in stitching. Hence it has been customary to first form the stitching in the comforter case, usually according to a design, leaving openings in the stitching through which a tube could be inserted to blow the down into the numerous passages formed in the case by the stitching. Thereafter the case and these openings are stitched closed.

To reduce the cost of the comforter, it has been known to thoroughly mix down with wool, the latter being a much cheaper material, and to thus provide a bat or mixture which is much easier to handle than down. This method permitted the anchoring or restraining stitching to be applied last, without permitting eventual passage of down through the stitching openings. However, certain disadvantages resulted, in that this mixture or bat had much less heat retaining quality than a down filling, nor did it have the resilience which is so marked in the latter and adds to the attractiveness of the comforter. The wool that was intertwined around the down naturally served to bind and restrain it, producing an unduly compact bat.

One object of the present invention is to overcome the defects above noted and without producing disadvantages in so doing.

Particularly, it is an object of the invention to provide a method of making a filling comprising a layer of free down which can be placed in a practical manner in a comforter that is thereafter to be stitched.

A supplemental object is to furnish an improved arrangement such that the stitching can be applied to the down layer without distorting or bulging the same.

A further object of the invention is to provide an improved, novel method of making a comforter to enable it to be inexpensively produced and with the requisite uniformity in character.

Other objects and advantages of the invention will become apparent as the specification proceeds.

With the aforesaid objects in view, the invention consists in the novel method pointed out in the subjoined claims, and illustrated in the an-

nexed drawing, wherein like parts are designated by the same reference characters throughout the several views.

In the drawing:

Figure 1 is a plan view of a comforter made according to the invention with parts removed to show the construction.

Fig. 2 is an enlarged fragmentary sectional view thereof.

Fig. 3 is a diagrammatic isometric view showing a first step in my novel method, and the frame used in conjunction therewith.

Figs. 4, 5 and 6 are similar views showing succeeding method steps, but with parts of the frame removed.

Referring in detail to the drawing, 10 denotes a device such as a comforter, embodying the invention. The same may include a case 11 of a suitable flexible or limp material, such as a textile fabric. The case includes opposed upper and lower walls 12, 13 respectively, which are marginally stitched together to completely encase the laminated filling 14. Fastening means such as stitching 15 extend through the comforter at a series of spaced points or lines to interconnect the walls 12, 13, through the filling. This stitching serves to anchor the filling against shifting, and is desirably arranged according to a decorative design.

The filling 14 comprises a layer or pad 16 of a wooly material, and at least one layer 17 of a downy material. Preferably two layers of the latter, 17 and 18, are used, disposed along opposite faces of the wooly layer 16. The latter may have its opposed faces of wooly texture so as to tend to engage the particles of the downy material. The layers 17 and 18 are of substantially less thickness than the wooly layer 16, although the proportions may vary widely with the character of the comforter that is to be produced. Preferably the downy layers 17 and 18 lie in direct contact with the wooly layer 16 and with the walls of the case 11.

It will be understood that the layers 17, 18 consist of any suitable free downy material, such as down of the duck family. In this way the filling provides a comforter having an attractive highly resilient character, and surface portions having a high heat retaining quality and permitting the comforter to be used with equal efficiency with either side downward.

It will be noted that the stitching 15 is so coordinated with the filling as to hold the case walls 12, 13 in substantial contact with the wooly layer 16. This, while not absolutely essential, is

desirable in order to minimize the chances of particles of downy material working their way through the minute openings that result in the fabric of the case due to the stitching. For this purpose, the stitching is effected under relatively high tension. Since the layer 16 may consist of wool, the fibers of the latter tend to reliably engage the down at the stitching to thus restrain movement of the down fibers.

10 The method of making the device 10 will now be described. A preformed pad or bat of carded wool whose fibers have been intertwined, such as the pad 16, is placed in the case 11. Then the longitudinal edges thereof are secured in a frame 19, with one end of the case open as at 20. The mode of securing may include longitudinal bars 21 interconnected as by clamp screws 21a and between which the edges of the case 11 are clamped. This frame is partially collapsible in any suitable manner so as to render the clamp devices 21 movable toward and away from each other to tension the case transversely or to permit it to sag between the clamping devices. Transverse bars 22 may be illustratively used, in fixed connection as at 23 with one clamping device or pair of bars 21, and in movable connection with the other clamping device, as by means of screw clamps 24 movable along the slots 25.

15 The first step of the method contemplates setting the clamping devices 21 toward each other so as to permit the lower case wall 13 to sag. This wall supports the wool pad 16. Upon lifting the upper case wall 12, the interior is fully accessible to receive a layer of downy material.

20 According to the second step shown in Fig. 4, the down is blown into the case in a suitable manner so as to permit it to settle relatively uniformly on the wool pad 16 to thus produce the layer 18. The fibrous, hairy free surface of the 25 wool pad aids in the distribution of the down. If desired, the down may be fed more toward the edges of the case to offset the tendency thereof to move down the concavity by the pad 16. Since the quantity of down supplied is relatively small, resulting in a comparatively thin down layer, the method of feeding can be accomplished in a practical manner.

25 As the third step, the frame 19 is expanded to move the clamping devices 21 apart as shown in Fig. 5, to thus render the case transversely taut in its horizontal plane. This causes the upper case wall 12 to rest snugly on the down layer 18 and restrain shifting of the down. Now, the operator may work or knead the upper surface portion of the article at and through the case wall 12, so as to effect a relatively perfect distribution of the down as may be desired.

30 As the fourth step, the expanded frame and its contents as in Fig. 5 is inverted so as to bring the bottom case wall 13 to the top to lie in a horizontal plane; now the frame is collapsed to permit the case wall 12 to sag as shown in Fig. 6. The wool pad 16 now lies on the down layer 18 and holds it securely in position. The upper case wall 13 is raised and the down layer 17 is furnished, all as hereinbefore described in connection with Figs. 4 and 5, it being apparent that the methods for providing the down layers 17, 18 are in all respects the same.

35 Finally, the case is sewn to close the opening 26, and the stitching 15 is applied to finish the comforter. In forming the stitching 15, the comforter may be securely pressed in advance of the line of stitching to tend to separate the down layers into sections. For instance, a sewing ma-

chine presser foot may be used which is considerably elongated in advance of the sewing needle, so that, as the comforter is moved with the presser foot engaged thereto, the down tends to separate somewhat as stated, thus permitting the 5 case walls to closely approach or to come into substantial contact with the wool pad 16. The bed or table of the sewing machine may have a similar device for the same purpose, if desired. It may be desirable to effect the sewing operations while the article is held in the expanded frame 19.

40 It will now be seen that I have provided an improved and novel method to permit a comforter to be manufactured in a satisfactory, economical manner, on a quantity production basis. Cotton, silk and other fibrous materials may be used in lieu of wool and are included in the term wooly materials. In the manufacture of comforters having fillings consisting entirely of down, the method herein disclosed is highly advantageous, especially the step shown in Fig. 5, since the down is reliably held while sewing the design as at 15, a step best accomplished while the comforter is held as in Fig. 5.

45 I claim:

1. The method of making a comforter including placing a pad having free wooly surfaces into a case of a limp material, expanding said case to raise the upper wall thereof with the pad resting 30 horizontally on a lower wall of the case, placing a relatively small quantity of loose downy material into the case so as to be adapted to form a relatively thin layer on a surface of said pad throughout the same, flattening said case so that the 35 downy material lies snugly retained between the pad and the upper wall of the case, inverting the case and its contents in the flat condition of the case so that the pad rests on the downy material, expanding said case to expose the upper surface 40 of the pad, again placing a relatively small quantity of loose downy material into the case to form a relatively thin layer on said surface of the pad, then flattening the case as hereinbefore stated, and closing the case and stitching through 45 the case, the pad and the layers of down material to thus restrain movement of the downy material.

2. The method of making a comforter including placing a pad having free wooly surfaces into a case of a limp material, expanding said case to 50 raise the upper wall thereof with the pad resting horizontally on a lower wall of the case, blowing a relatively small quantity of downy material into the case so as to be adapted to form a relatively thin layer on a surface of said pad throughout the 55 same, flattening said case so that the downy material lies snugly retained between the pad and the upper wall of the case, then working the upper wall of said case to cause an even distribution of the down in the case, inverting the case 60 so that the pad rests on the downy material, expanding the case in the inverted position thereof to expose the upper surface of the pad, again blowing a relatively small quantity of a downy material into the case to form a relatively thin 65 layer on the said exposed surface of the pad, flattening the case to snugly embrace the downy material, working the upper wall of the case to evenly distribute the downy material, closing and stitching through the case, the pad and the layers 70 of downy material to restrain movement thereof.

3. The method of making a comforter including generally horizontally supporting at opposite edges a case having therein a pad having a wooly surface, moving said edges toward each other to 75

permit the lower case wall that supports the pad to concave, raising the upper case wall and distributing loose downy material into the case upon said wooly surface, moving the said edges apart 5 to render the case taut, working said upper case wall to evenly distribute the downy material, and then securing the downy material against shifting in the case.

4. The method of making a comforter including generally horizontally supporting at opposite edges a case having therein a pad having a woolly surface, moving said edges toward each other to permit the lower case wall that supports the pad to sag, with consequent sagging of the pad that 10 rests on the lower wall, raising the upper case 15 wall, charging downy material into the case upon said woolly surface in lesser quantity at the lower said portions of the pad, moving than at the higher portions of the pad, moving

said edges apart to render the case taut, working the upper wall of the case to evenly distribute the downy material, and interconnecting the pad and the case along a series of lines to restrain shifting of the downy material.

5. The method of making a comforter including generally horizontally supporting a comforter case at opposite edges thereof, with said opposite edges moved toward each other and with the lower case wall sagging downwardly, raising the upper case wall and distributing loose filling material into the case upon the lower case wall, moving the said opposite edges apart to render the case taut to restrain movement of the filling material, and then securing the filling material 10 15 against shifting in the case.

JULIUS DAVIS.
